DESIGN FOR BAR MATERIAL FOR OPHTHALMIC MOUNTINGS

Edward M. Splaine, Southbridge, Mass., assignor
to American Optical Company, Southbridge,
Mass., a voluntary association of Massachu-
sets

Application June 29, 1938, Serial No. 78,153

Term of patent 14 years

To all whom it may concern:

Be it known that I, Edward M. Splaine, a citizen of the United States of America, residing at Southbridge, in the county of Worcester and State of Massachusetts, have invented a new, original, and ornamental Design for Bar Material for Ophthalmic Mountings, of which the following is a specification, reference being made to the accompanying drawing, forming a part thereof.

The figure in the drawing is a greatly enlarged perspective view of a piece of bar material for use in forming parts of an ophthalmic mounting and embodying my new design.

The characteristic features of the design reside in the provision of a bar member having a central, relatively smooth, longitudinal surface and angularly disposed corrugated, longitudinal

side surfaces on the outer face thereof. The corrugated side surfaces are so angled as to reduce the edge surfaces of the bar to have a relatively narrow appearance when light impinges thereon. The central surface produces a relatively brilliant ribbon-like band when light impinges thereon and the angularly disposed corrugated side surfaces produce a dull satin-like appearance when viewed at a distance therefrom.

The essential features of the design reside in the portions of the bar which are shown in full lines in the drawing.

I claim:

The ornamental design for bar material for ophthalmic mountings, substantially as shown and described.

EDWARD M. SPLAINE.
